UNITED STATES PATENT OFFICE

2,436,731

GARMENT FINISHING MACHINE

John H. Richa, Kansas City, Mo.

Application October 15, 1945, Serial No. 622,251

13 Claims. (Cl. 223—57)

1

This invention relates to garment finishing machines of the type disclosed in United States Letters Patent No. 2,284,232, issued to me May 26, 1942.

Finishing machines of this character require a form for supporting a permeable bag and over which a garment is applied so that the garment is steamed and brought to shape by steam and/or air discharged into the bag. The machine illustrated in the patent is particularly adapted to finish garments of coat-like character but it is difficult and sometimes impossible to apply dresses and similar narrow-waisted garments over the form for the reason that the waists of such garments will not pass over the shoulder portions of the form.

It is, therefore, a principal object of the present invention to provide a garment finishing machine with a permeable bag supporting form having collapsible shoulder portions so as to facilitate application of a dress or a similar garment.

It is also an object of the invention to provide a form with adjustable neck and shoulder elements to facilitate shaping of the form to the neck and shoulder portions of a garment.

Other objects of the invention are to provide a form that is simple and inexpensive to construct and which is readily operated and adjusted to support a garment over a permeable bag.

In accomplishing these and other objects of the invention, I have provided improved structure, the preferred form of which is illustrated in the accompanying drawing wherein:

Fig. 1 is a perspective view of a garment finishing machine embodying the features of the present invention, the upper portion of the permeable bag being broken away to better illustrate the supporting form therefor, the shoulder portions of the form being shown in extended position.

Fig. 2 is a similar view showing the shoulder portions of the form in collapsed position for facilitating passage of the waist portion of a garment thereover.

Fig. 3 is an enlarged detail section through the neck portion of the form; particularly illustrating the latch for retaining the shoulder supporting arms in extended position.

Fig. 4 is a cross section on the line 4—4 of Fig. 3.

Fig. 5 is a vertical section through the upper portion of the bag and its supporting form showing the shoulder supporting arms in extended position.

Fig. 6 is a similar section but showing the shoulder supporting arms in collapsed position.

Fig. 7 is a section particularly illustrating pivotal mounting of the neck element of the form and showing the neck element adjusted to accommodate a garment tailored for a person having an erect posture.

Fig. 8 is a similar section but showing the neck adjusted to a garment tailored to a person having a stooped or rounded shoulder posture.

Referring more in detail to the drawings:

- 10 1 designates a garment finishing machine constructed in accordance with the present invention and especially adapted for finishing dresses and similar small-waisted garments. The machine includes a base 2 for containing a source of heated air under pressure such as a motor actuated blower (not shown), steam supply lines and valves (also not shown) for controlling flow of steam and air into a fabric covered distributor 3 that projects upwardly from the base. Mounted on the upper end of the distributor is a bracket 4 carrying a form assembly 6 including a neck element 7 and laterally extending shoulder elements 8 and 9 which suspendingly support a permeable bag 10 having the general shape of a dress or similar garment. The bracket 4 includes a foot 11 connected with the distributor 3 by a fastening device such as a bolt 12 and on which the bracket is adapted to rotate about a vertical axis. The foot portion of the bracket carries laterally 15 spaced upwardly extending members 13 and 14 offset from the axis of movement of the bracket for a purpose later described. The upper ends of the members 13 and 14 curve forwardly to journal trunnions 15 and 16 projecting laterally of a block 17 carrying the neck element of the form. In the illustrated instance the trunnions consist of cap screws having their shanks extending through openings 18 in the members 13 and 14 and into threaded sockets 19 of the block as best 20 shown in Figs. 5 and 6. The neck element includes a neck portion 20, back portion 21, breast portion 22, and laterally extending shoulder portions 23 and 24 generally conforming to the corresponding parts of the wearer of a garment to be finished on the machine.

The neck element of the form may be constructed of suitable material and is preferably of hollow character so as to accommodate working parts of the form now to be described.

- 25 Extending laterally of the block 17 below the shoulder portions 23 and 24 are ears 25 mounting pivot pins 26 for pivotally connecting shoulder supporting arms 27 and 28 and on which the arms are adapted to move from an extended position 30 shown in Fig. 5 to a collapsed position shown in

Fig. 6. The shoulder supporting arms may be of any suitable shape but are illustrated as being of substantially channel-shape cross section having web portions 29 and side flanges 30 and 31, the web portions being cut out in the pivoted ends to accommodate the ears 25 and pins 26 of the block.

Slidably supported at the outer ends of the arms are extensions 32 and 33 carrying shoulder supporting pads 34 and 35 adapted to engage within the shoulder portions of a garment. The extensions with the arm may comprise headed studs 36 fixed to and projecting from the inner faces of the web portions of the arms. Said extensions have elongated slots 37 through which the pins pass as shown in Fig. 5 while the sides of the extensions are supported between the flanges of the arms so that they are readily manipulated to adjust the pads 34 and 35 to garments of different shoulder widths. The arms are supported in extended position by links 38 and 39 having one end pivotally connected with ears 41 and 42 on a collar 43 attached to a rod 44, the connections of the links with the ears being provided by pivot pins 45 and 46 and the connections with the arms by pins 45' and 46'. The rod 44 is reciprocable through a bore 47 in the block 17 and is normally urged in arm collapsing position by a coil spring 48 having one end bearing against the collar 43 and its other end against the underside of the block 17. It is thus obvious that expansion of the spring forces the rod 43 downwardly to carry the collar 43 therewith and exert a downward pull on the arms through the link connections 38 and 39. The arms are latched in extended position by providing the rod with an annular groove 49 which is adapted to be engaged by a latch plate 50 when the arms are extended. The latch plate is reciprocably mounted transversely of the neck portion of the form and carried between supporting plates 51 and 52. The latch plate 50 has a slot-like opening 53 for passing the rod and to permit reciprocation of the plate so that the edge 54 of the slot may be moved out of latching engagement with the latch groove of the rod. The latch plate is normally urged to latching position by a coil spring 55 sleeved over a tongue 56 on the plate and having one end bearing against the latch plate and its opposite end against the neck portion of the form. The latch plate is moved to unlatching position against action of the spring 55 by a push button 57 fixed to a forward extension 58 of the latch plate. The extension 58 projects through an opening 59 in the neck portion of the form as best shown in Figs. 3 and 4. The neck element including the shoulder supporting arm thus provides a unit pivotally mounted on the axis of the trunnions 15 and 16 so that the neck may be tilted forwardly or re-tractively as shown in Figs. 7 and 8 to adjust the form to the neck and shoulder portions of the garment.

In order to facilitate movement of the assembly the neck may be provided with an upwardly extending handle 60, which handle may be gripped by the hand to position the neck portion of the form in the garment.

The bag 10 generally conforms to the shape of a dress and includes a waist portion 61 and skirt portion 62. The bag also has shoulder portions 63 and 64 and sleeves 65 and 66, the lower ends of the sleeves being closed to retain the steam or air in the bag as later described, and weighted to facilitate insertion in the sleeve of a garment. The bag is of larger size than the largest size garment to be finished on the form so that when the bag is inflated the garment will be extended to its original shape.

In using the machine, the supporting arms 27 and 28 of the form are released by pushing on the button 57 to effect release of the latch plate 50 from the latch groove 49 of the rod 44. The spring 48 then expands to shift the collar 43 downwardly and effect collapse of the shoulder supporting arms to the position shown in Fig. 6. When the arms are collapsed the width of the form is of less size than the waist portion of a dress to be placed thereover.

A dress may then be applied over the bag 10 by drawing the skirt thereof over the top of the form. The sleeve portions 65 and 66 of the bag 10 are then drawn into the sleeves of the dress whereupon the shoulder supporting arms 27 and 28 are grasped and raised to garment-supporting position. When the arms are being raised, the collar 43 moves upwardly against the action of the spring 48 to compress the spring and move the groove 49 of the rod 44 into latching engagement with the latch plate 50. As soon as the annular groove 49 in the rod registers with the latch plate, the spring 55 (Figs. 3 and 4) will urge the plate into latching contact with the groove. The arms are thus supported to carry the shoulder portion of the garment in proper position. The shoulder arm extensions 32 and 33 are then adjusted to conform to the shoulder width of the garment. The handle 60 on the neck element of the form is tilted to position the neck element within the garment so that the back of the garment fits smoothly thereover; for example, if the dress has been tailored for a person with a stooped posture it will be necessary to move the neck portion of the form into the approximate position shown in Fig. 8. During this movement the rod 44, spring 48 and shoulder supporting arms 27 and 28 tilt; however, due to the offset of the vertical members 13 and 14 of the form, the neck element of the form has ample movement.

The garment is then steamed as in accordance with the method disclosed in the above mentioned patent. This is effected by introducing steam into the bag by way of the distributor 3 to inflate the bag and cause the steam to permeate through the bag into contact with the garment for softening and raising the fibers. After steaming, the steam supply is shut off and heated air is discharged into the bag to inflate the bag so as to extend the garment to its original shape, the air supply being maintained until the garment is dried to shape whereupon pressure is applied to the button 57 to release the latch plate 50 from latching engagement with the rod 44. The spring 48 is then effective in collapsing the arms to the position shown in Figs. 2 and 6 whereupon the dress is readily removed over the top of the form.

From the foregoing it is obvious that I have provided a garment finishing machine particularly adapted for finishing narrow-waist garments such as dresses.

It is also obvious that the garments may be readily applied and removed from the form without stretching or tearing the fabric or restricted portions thereof.

It is further obvious that when the supporting arms are extended the bag and garment carried thereon are supported in proper position for the finishing process.

It is also obvious that the neck element of the

form may be adjusted to conform to the neck portion of any garment applied thereon.

What I claim and desire to secure by Letters Patent is:

1. In a garment finishing apparatus, a neck form for supporting the neck portion of a garment, collapsible shoulder supporting means extending laterally of the neck form, means for shifting the shoulder supporting means from a collapsed position to a position for supporting shoulder portions of the garment, and means for tilting the neck form relatively to the back and shoulder portions of the garment.

2. In a garment finishing apparatus, a neck form for supporting the neck portion of a garment, collapsible shoulder supporting means extending laterally of the neck form and having portions for engaging under tips of the shoulder portions of a garment, means for shifting the shoulder supporting means from a collapsed position to a position for supporting said shoulder portions of the garment, and means for tilting the neck form relatively to the back and shoulder portions of the garment.

3. In a garment finishing apparatus, a form including a neck member for supporting the neck portion of a garment, an inflatable bag covering the form and having shoulder and sleeve supporting portions, shoulder supporting means extending laterally of the neck member and having portions for engaging within the shoulder supporting portions of the bag, means for collapsing said shoulder supporting means to facilitate application of a garment over the bag, means for shifting the shoulder supporting means from collapsed position to supporting position, and means for tilting the neck member relatively to the back and shoulder portions of the garment when the garment is placed on the bag.

4. In a garment finishing apparatus, a permeable bag having shoulder portions corresponding to the shoulders of a garment, a neck form adapted to cooperate with the bag in shaping a garment placed on the bag, shoulder supporting means extending laterally of the neck form and having portions for engaging under tips of the shoulder portions of the bag, means for moving said shoulder supporting means to facilitate application of the garment over said bag, and means for tilting the neck form relatively to the back and shoulder portions of the garment when placed on the bag.

5. A garment finishing apparatus including, a neck form, means for rotatably supporting the neck form for movement about a vertical axis, collapsible shoulder supporting means extending laterally of the neck form, means for collapsing said shoulder supporting means to facilitate application of the garment over said shoulder supporting means, and means for shifting the shoulder supporting means from said collapsed position to a position for supporting said shoulder portions of the garment.

6. A garment finishing apparatus including, a neck form, means for supporting the neck form for movement about a vertical axis on the support, a permeable bag movable with the neck form, shoulder supporting means extending laterally of the neck form and having portions for engaging the bag, means for collapsing said shoulder supporting means to facilitate application of a garment over the bag, and means for shifting the shoulder supporting means from said collapsed position to supporting position.

7. A garment finishing apparatus including, a

support, a neck form rotatable about a vertical axis on the support, shoulder supporting means extending laterally of the neck form and having portions for engaging under tips of the shoulder portions of the garment, means for collapsing said shoulder supporting means to facilitate application of the garment over said shoulder supporting means, means for shifting the shoulder supporting means from said collapsed position to a position for supporting said shoulder portions of the garment, and means for tilting the neck form relatively to the back and shoulder portions of the garment.

8. A garment finishing apparatus including, a support, a neck form rotatable about a vertical axis on the support, a permeable bag suspended from the neck form, shoulder supporting means extending laterally of the neck form and having portions for engaging the bag, means for collapsing said shoulder supporting means to facilitate application of the garment over said shoulder supporting means, means for shifting the shoulder supporting means from said collapsed position to a position for supporting said bag, and means for tilting the neck form relatively to the back and shoulder portions of the garment.

9. A garment finishing apparatus including, a support, a neck form, a bracket carrying the neck form on the support, laterally extending shoulder supporting arms pivotally connected with said bracket, a rod slidably carried by the bracket, links connecting the shoulder supporting arms with said rod, latch means engageable with the rod when the shoulder supporting arms are in extended position to support said arms, and means for releasing said latch means.

10. A garment finishing apparatus including, a support, a neck form, a bracket carrying the neck form on the support, laterally extending shoulder supports pivotally connected with said bracket, a rod slidably carried by the bracket, links connecting the shoulder supports with said rod, latch means engageable with the rod when the shoulder supports are in extended position, means for releasing said latch means, and a spring for urging said shoulder supports into collapsed position on release of the latch means.

11. A garment finishing apparatus including, a support, a neck form, a bracket carrying the neck form on the support, means pivotally connecting the bracket with the support, laterally extending shoulder supports pivotally connected with said bracket, a rod slidably carried by the bracket, links connecting the shoulder supports with said rod, latch means engageable with the rod when the shoulder supports are in extended position, and means for releasing said latch means.

12. A garment finishing apparatus including, a support, a neck form, a bracket, trunnions for pivotally mounting the neck form on the bracket, laterally extending shoulder supports carried with the neck form, means for swivelly mounting the bracket on the support, a rod slidably carried with the neck form, links connecting the shoulder supports with said rod, latch means engageable with the rod when the shoulder supports are in extended position, and means for releasing said latch means.

13. In a garment finishing apparatus including a neck form, a latch plate having a slot, means slidably mounting the latch plate on the neck form, laterally extending shoulder supports, a rod support fixed to the neck form, a rod slidably carried by the rod support and extending through

the slot of the latch plate, links connecting the shoulder supports with said rod, said rod having a portion to be engaged by the latch plate when the shoulder supports are in extended position, means for releasing said latch plate from engagement with the engaging portion of the rod, and a spring for urging said shoulder supports into collapsed position on release of the latch plate.
